[57] **CLAIM**

The ornamental design for running light for boat trailer and the like, as shown and described.

DESCRIPTION

FIG. 1 is a perspective view of the running light for boat trailer and the like showing my new design.

FIG. 2 is a side elevational view thereof on an enlarged scale.

FIG. 3 is a front elevational view thereof on an enlarged scale.

FIG. 4 is a plan view thereof on an enlarged scale from the top.

FIG. 5 is a side elevational view thereof on an enlarged scale taken from the side opposite FIG. 2.

FIG. 6 is a plan view thereof on an enlarged scale taken from the bottom.

FIG. 7 is a rear elevational view thereof.
